Redding & Greeley

UNITED STATES PATENT OFFICE.

POUL HANSEN, OF HELLERUP, NEAR COPENHAGEN, DENMARK, ASSIGNOR TO F. L. SMIDTH & COMPANY, OF NEW YORK, N. Y., A CORPORATION OF NEW JERSEY.

HYDRAULIC PRESS.

Application filed December 16, 1922. Serial No. 607,462.

To all whom it may concern:

Be it known that I, POUL HANSEN, a subject of the King of Denmark, residing at 11 Rebekkavej, Hellerup, near Copenhagen, Denmark, have invented certain new and useful Improvements in Hydraulic Presses, of which the following is a specification, reference being had to the accompanying drawing, forming a part hereof.

This invention has been developed with especial reference to its application to presses designed for use in the formation of sewer pipes, drain pipes, etc., from clay, which is forced by a plunger through a suitable die or former. It will be seen, however, as this description proceeds, that the invention is independent of the particular use to which it is applied and that presses which embody the invention can be used for other purposes than that indicated. In the apparatus which has been chosen for illustration as an embodiment of the invention the pipe-forming plunger is carried by the piston of the press and water or other suitable liquid is supplied to the cylinder of the press, at each end thereof, from a constantly operating pump, preferably a centrifugal pump, the number of revolutions of the pump being kept constant while the quantity of water delivered in a unit of time is varied as the conditions of operation require. Provision is made whereby the movement of the piston and therefore of the plunger of the press can be controlled at the will of the operator, while the piston is brought gradually to rest at either extreme of its movement without necessitating action on the part of the operator. The invention will be explained more fully hereinafter with reference to the accompanying drawing in which it is illustrated and in which—

Figure 1 is a view partly in vertical section and partly in elevation of a press which embodies the invention.

Figure 2 is a detail view in section showing a portion of the cylinder and the piston with its check valves.

Figure 3 is a detail view showing a portion of the piston in section with its check valves.

In the embodiment of the invention illustrated in the drawing, a centrifugal pump 1, of any suitable construction, is connected on its suction side, as by the pipe 2, with the discharge outlet 10 of the cylinder 6,

and on its delivery side, as by a pipe 3, with the intake of the valve chest 4. The plunger 5^a, which co-acts with the pipe-forming cylinder or die 5, in the usual manner, is carried by rods 5^b which are secured to the piston 15 and are extended through suitable stuffing boxes in the head of the cylinder, both ends of which are closed. The valve chest 4 is connected with the respective ends of the cylinder 6 through channels 8 and 9 which terminate in the wall of the cylinder in tapered or heart-shaped ports as shown at 18 in Figure 3. Within the valve chest 4 is a slide valve 7 the ends of which are arranged to lap the outer ends of the channels 8 and 9, while the recess 7^a in the working face of the slide valve is adapted to place one or the other of the ports 8, 9, as the case may be, in communication with the chamber 10^a of the discharge port 10. For convenience in operation the stem 11 of the slide valve 7 is connected by a link 12 with one arm of a bell crank lever 13 provided with a handle 14.

The piston 15 does not itself lap the ports 18 of the channels 8 and 9 in the extreme positions of the piston but is provided with pivoted check valves 16 on its upper and lower faces which respectively lap the channels 8 and 9 in the extreme positions of the piston, such check valves moving freely to permit the delivery of water into the cylinder, as indicated by broken lines in Figure 2, but moving to closed position, as shown by full lines in Figure 2 under the influence of the water as it is discharged from the cylinder at one end or the other, as the case may be.

In describing the operation of the press it will be assumed that the piston 15 is at the beginning of its forward stroke, the slide valve 7 having been moved by the operator so as to place the delivery side of the pump 1 in communication with the upper end of the cylinder 6. The movement of the piston can be checked at any time, if desired, by movement of the slide valve 7, but the piston will be gradually brought to rest as it approaches its extreme position without the attention of the operator by reason of the fact that the valve 17 on the forward face of the piston, as the piston approaches the limit of its forward movement, will lap the port of the channel 9, thereby gradually cutting off the return of water from the forward end 110

of the cylinder to the intake of the pump 1. In the upward or return movement of the piston, initiated by proper movement of the slide valve 7, the upper check valve 16 will 5 in like manner gradually cut off the return of water from the upper end of the cylinder to the pump and gradually bring the piston to rest.

It will be seen that the pump 1 is permitted to operate continuously, the delivery of 10 water to the press cylinder being controlled either by cutting off the inflow, at the will of the operator, or by cutting off the return of water to the suction side of the pump by 15 the automatic action described. It will further be observed that although the forward movement of the piston may be slow, as determined by the resistance, the return movement of the piston will be rapid.

20 It will be understood that various changes in details of construction and arrangement can be made to suit different conditions of use and that the invention, except as pointed out in the claims, is not limited to the particular construction shown and described 25 herein.

I claim as my invention:

1. In a press, the combination of a cylinder, a piston, an hydraulic pump, means whereby the discharge of the pump can be 30 connected to either end of the cylinder, and the suction of the pump can be connected to the other end of the cylinder, and check valves carried by the piston on opposite faces and adapted to cut off communication between the cylinder and the pump at the corresponding end as the piston approaches the limit of its stroke in either direction.

2. In a press, the combination of a cylinder having a valve chest with channels opening in the cylinder wall at the respective ends, and an exhaust chamber, an hydraulic pump having a connection on the discharge side to the valve chest and on the suction side to the exhaust chamber; a valve to control the connections between the valve chest and exhaust chamber on one hand and the respective ends of the cylinder on the other hand, a piston, and check valves carried by the piston on opposite faces to close the corresponding port in the wall of the cylinder as the piston approaches the limit of its stroke in either direction.

This specification signed this 29th day of November, A. D. 1922.

POUL HANSEN.
